UNITED STATES PATENT OFFICE.

HENRY F. PARSONS, OF SAN FRANCISCO, CALIFORNIA, ASSIGNOR TO DANIEL COOK, OF SAME PLACE.

ROCK-DRILLING MACHINE.

SPECIFICATION forming part of Letters Patent No. 248,787, dated October 25, 1881.

Application filed June 30, 1881. (No model.)

To all whom it may concern:

Be it known that I, HENRY F. PARSONS, of San Francisco, in the county of San Francisco and State of California, have invented a new 5 and useful Improvement in Drill-Machines, of which the following is a description which will enable others skilled in the art to construct and use the same.

The object of my invention is to construct 10 a drill-machine which can be conveniently worked by hand, and which will so operate as to cause the drill while resting on the rock to receive repeated blows from a hammer, the drill being preferably retracted and partially 15 revolved and returned again in contact with the rock between the blows of the hammer, the operating mechanism being so sustained that it is fed forward as the drill proceeds in the rock, and is thus caused to occupy continually 20 the same position with reference to the top of the drill or drill-rod.

I will now proceed to describe one of the forms in which I prefer to construct my machine.

25 Figure 1 is a front view of the machine arranged for drilling in a vertically-downward direction. Fig. 2 is a side view of the machine in the same position. Fig. 3 is a sectional side view arranged for drilling downward in a direction 30 slightly inclined from the perpendicular. Fig. 4 is a section through the line $x x$ of Fig. 1. Fig. 5. represents the drill-holder detached. Fig. 6 represents the steadyng-bar in the position it would occupy if the machine were being 35 used to drill upwardly at an angle of about forty-five degrees from the perpendicular, and also the supporting devices for supporting the machine in that position. The other portions of the machine are omitted in this figure, but 40 are to occupy the same position relatively to the steadyng-bar, as shown in the other figures.

A represents the steadyng-bar of the machine. This is simply a straight bar of metal 45 of uniform thickness with its front end pointed or otherwise formed, so as to take into or hold and remain in a fixed position on the face of the rock when pressed against it. When the bar is pointed a small indentation can be made 50 in the rock to receive the point. On the opposite end of this bar a cushion, pad, or breast-

plate, B, is secured, and against this plate the operator will lean when he is working the machine, so as to press the opposite point against the rock and keep the machine steady. 55

C is the barrel of the machine, through which the drill holder passes, and in which it is held and operated. This barrel is several inches in length, and has a passage or hole extending longitudinally through its upper portion, and 60 of a size to correspond with the size or thickness of the steadyng-bar, so as to receive the bar and allow the barrel to be shifted upon it to any point of its length. The under side of this steadyng-bar is slotted longitudinally, 65 and a projecting rib or feather, provided on the inside of the hole or bore of the barrel, enters and works in this slot in order to prevent the barrel from turning on the bar, but to allow it to move longitudinally on the bar from 70 one end toward the other. Through the rear end of this barrel, and across or in a direction transverse to the steadyng-bar, passes the crank-shaft D by which the drill is operated. On each end of this shaft is a crank, E, to permit the operator to use both hands in turning the shaft. This shaft D runs through a transverse hole or bore in the rear part of the barrel, and it is supported at each side in suitable 75 bearings. 80

To the side of the barrel C, at its rear end, is bolted an arm, F, projecting outward at right angles from the barrel, and connected at its outer end with an angle-brace, h. This arm F also extends on each side of the barrel, so as 85 to form bearings for the shaft D at F F, Fig. 1. The end of the angle-brace has a box or slotted piece, in which is fastened the lower end of a strong bent spring, J. From this fixed point the spring J bends upward and inward 90 to a position at the rear of the barrel C, in which position is secured to it a heavy hammer block or head, K.

The drill-holder L is a round bar, which fits 95 and is supported in a bore or cylindrical chamber in the barrel C, directly below and parallel with the hole for the steadyng-bar A. In the forward end of this bar L is a socket in which is placed the end of the drill-rod or boring-tool M, and when inserted in this socket the tool is 100 secured by means of set-screws n. The drill-rod will then project beneath and parallel with

the steadyng-bar, and will strike the rock below the pointed end of the bar. This drill-holder extends through and projects beyond the rear end of the barrel C, and in this end of the holder is a socket, in which is screwed a short striking-pin, *p*, that receives the blows of the spring-hammer. To hold this pin in place the socket end of the holder is split, and on its surface is cut a left-hand thread, over which fits a nut, *t*, and as this end is made tapering the nut *t*, when screwed down, will close the split parts firmly around the inserted pin and hold it in place in the socket. By this construction the striking-pin can be renewed when worn down.

At the middle of the barrel C, and below the line of the bore wherein the steadyng-bar works, a transverse opening or slot is made entirely through the sides of the barrel, and with its center in line with the axis or center line of the drill-rod bore. This slot divides the drill-rod bore into two portions, and it is made to receive a ratchet-face hollow nut, *T*, that has on the outside of the barrel C, at one side, a spring-pawl, *w*, to bear against the ratchet-face of this nut. The aperture through the nut *T* coincides with the bore or chamber that receives the drill-rod holder *L*, and the holder passes through and moves in this ratchet-face nut. These two parts are connected together, so that when sliding in one direction in the barrel C the drill-holder shall turn or rotate the nut *T* backward for the distance of one ratchet tooth, but shall have of itself no rotation while moving backward in the barrel, and when sliding in the other direction through the nut *T* it shall be caused to rotate as it moves forward, while the nut is held stationary. This is effected by making in the exterior surface of the holder *L* several short spiral grooves, *w*, into which a corresponding number of spiral ribs, *v*, provided on the interior surface of the hollow nut are made to fit. This nut will turn freely in one direction, but will be locked and held by the pawl *w* from turning in the opposite direction. Consequently, when the drill-holder is caused to move in one direction or backward within the barrel C, the ratchet-face nut will be rotated by the action of the spiral grooves on the holder and the ribs *v* within the hollow of the nut; but when the drill-holder moves in the opposite direction, or forward, the nut *T*, being held by its pawls, will not turn in the other direction, but will be locked, so that the spiral grooves and ribs then react upon the drill-rod holder and cause it to rotate as it moves forward in the barrel. This rotation of the drill-holder *L* produces a change in the position of the end of the drill while at work, so that it shall not strike always in the same place at the bottom of the hole, but shall be regularly rotated as the operation of drilling goes on. Upon and surrounding the forward end of this drill-holder is a strong coil-spring, *S*, that presses against a shoulder, *N*, on the drill-

holder, so as to force the tool forward and keep it against the bottom of the hole being made. The rear end of this spring rests against a fixed shoulder within the bore or chamber in the 70 barrel wherein the drill-holder moves.

The spring-hammer *K*, which operates against the striking-pin *p* in the end of the drill-holder *L*, has on each side a forwardly-projecting arm, *R*, extending toward the crank-shaft *D*, and furnished on the end with a stud and friction-roller, *l*. These arms are arranged one on each side of the barrel and in line with the cams *V*, so as to be struck and forced backward by them. As the crank-shaft is rotated 80 these cams *V* act against the arms *R* and force back the hammer, and as they are double cams, or with two surfaces or members, they produce two backward movements of the hammer to one revolution of the shaft *D*. When the 85 crank-shaft is rotated by the cranks on its ends the cams *V* strike the friction-rollers on the arm *R* and force back the hammer until the ends of the cams slip from the rollers *l*, when the hammer is thrown forward with force 90 against the end of the drill-holder by the reaction of the spring. Thus at each blow of the hammer the tool in the end of the drill-holder is forced into the rock or substance to be drilled. Smaller cams *X* are also secured 95 on the crank-shaft *D*, one on each side of the barrel and between it and the larger cams *V*, in a position to strike against a cross-head, *Y*, that is fixed on the rear end of the drill-holder and projects laterally at both sides. These 100 cams *X* act against this cross-head *Y* to retract or draw the drill-holder backward and the drill out of the bottom of the hole a short distance after every blow of the hammer to prepare the drill for the next stroke. These cams *X* are 105 shorter than the hammer-actuating cams *V*, and the cross-head *Y* slips from their points and the drill-holder *L* is returned to its forward position by the coil-spring on its front, and before the hammer is ready to make the 110 next blow.

Two adjustable supports, *P P*, are attached to the machine for holding it in position at the required height. They consist of the telescopic legs secured to the crank-shaft and on 115 each side of the barrel, and capable of being lengthened or shortened, as required, to bring the drill at the desired point for work. They extend downward at a diverging angle, and they have journal-boxes with hinged or removable caps to fit on the crank-shaft *D*, for the purpose of allowing the legs to be removed from this part of the machine and shifted back to the end of the steadyng-bar where the breast-plate is fixed. To receive these legs *P* a stud 120 or journal, *r*, is formed on each end of the breastplate, and these supports *P* can be removed from the crank-shaft and fixed to the breastplate when desired. The object of this arrangement is to enable the level of the steadyng-bar to be maintained as the barrel moves forward, because the motion of the barrel as 125 130

the drilling progresses would change the angle of the drill if the legs were centered on the crank-shaft. In some cases this adjustment will not be required, and then it will be more 5 convenient to have the legs support the machine at the crank-shaft; but when it is necessary to have the drill move forward in substantially a straight line the legs are to be attached to the breastplate.

10 When working the machine in positions where it would be difficult or impractical to lean and press against the breastplate—as, for example, if the steadyng-bar should be in the position represented, as at Fig. 6—I employ an 15 adjustable support having a clamping-piece, 1, for fixing it to the back of the breastplate B, and an extension-leg hinged or pivoted to the back of this clamp, so as to be set at any required inclination. This leg is adjustable in 20 length by being formed in part of a hollow tube, 2, with a telescopic leg, 3, in the lower end, and a screw-rod, 5, in the upper end that works in the tube and through a hand-nut, 6, by which it is changed in length and held at 25 any point of adjustment. The screw-rod 5 is attached to the back of the clamping-piece 1, and by turning the hand-nut 6 the support is kept of the required length behind the machine to maintain a continuous support and pressure 30 against the end of the steadyng-bar as the drill moves forward into the rock.

When beginning work with a long drill the steadyng-bar can, if necessary, be increased in length by attaching to its front end a supplemental bar provided with a socket on its 35 rear end to receive and be secured to the front end of the steadyng-bar A.

40 The operation of the machine will be as follows: The point of the steadyng-bar is set against the rock to be bored, and the legs are braced and adjusted to the inequalities of the surface, so as to support the weight of the machine. The operator throws his weight upon the rear end of the steadyng-bar by pressing 45 against the breastplate, and reaching forward turns the shaft D by means of the hand-cranks E. The coil-spring S holds the drilling-tool with a strong pressure against the face of the rock, and as the crank-shaft is rotated the long 50 cams V force the hammer back and then release it, so that it flies forward quickly and strikes the rear end of the drill-holder and drives the drill into the rock. The short cams X then draw the drill-holder back a short distance, but quickly release it and allow the 55 coil-spring to throw it forward into position again before the hammer gives another blow. By this movement of the drill-holder its rotation is effected in the following manner for the 60 purpose of turning the drill in the hole: When the drill-holder is drawn back by the short cams the hollow ratchet-face nut T on the center part of the holder will be rotated in the barrel the distance of one tooth or ratchet by 65 the action of the spiral grooves and projections v v on the holder and in the bore of the

hollow nut; but when the drill-holder moves forward again the nut T is locked by the pawl w and will not rotate, but will cause the spirals to give a short rotating movement to the 70 drill-holder L as it moves forward in the barrel and through the hollow nut. The drill is thus turned at each forward movement of the drill-holder before it is struck by the hammer.

75 The drill and the hammer-supporting mechanism are fed forward on the steadyng-bar in the following manner: A friction-brake, f, is applied to the steadyng-bar A at the barrel C by means of the screw-shaft e, which extends out through the barrel, and is provided on its 80 outer end with the regulating-screw g. The brake f is pressed against the face of the steadyng-bar by turning the regulating-screw with a pressure that is regulated as required, so that the stroke of the hammer, as it is received against the end of the drill-holder, acts also against the rear end of the barrel C and forces it forward upon the steadyng-bar as fast as the drill enters the rock. The forward travel of the barrel C upon the steadyng bar 90 will be controlled by the amount of pressure put upon the brake. A short spiral spring is placed between the regulating-screw and the barrel. A piece of leather, d, or other cushion, is placed against the rear end of the barrel 95 to ease the stroke of the hammer against it.

100 The tension of the spring J can be increased by adding additional leaves to it so as to increase the striking force of the hammer K when required.

105 Although I have shown a flat spring, springs of other forms may be used; but I prefer a flat spring because it acts more quickly, and because the hammer is more likely to strike a square blow under varying circumstances or were used.

110 I use a twisted drill-rod, M, in the machine, so that the rotation imparted to it by the spiral grooves and splines in the nut will cause the drillings to be discharged from the hole as fast as they are produced through the groove or grooves which extend spirally around the drill-rod upward from the point of the drill.

115 It will be noticed that the impact of the hammer is received by the short striking-pin p, which is secured in the end of the drill-rod so that it can be easily renewed.

120 I claim as my invention—
1. In combination, a tool-holder for holding the drilling-tool, a hammer driven against the tool-holder by a spring, a mechanism for drawing back the hammer and then releasing it to cause the spring to throw it against the end of the tool-holder, and a steadyng-bar by 125 which the machine is held and guided to its work, and upon which it is fed forward as the drilling progresses, substantially as hereinbefore described.

130 2. In combination, a tool-holder for holding the drilling-tool, a hammer giving its blow by the force of a spring and operated by mechan-

ism to strike a succession of blows against the rear end of the tool-holder, and a mechanism for giving to the tool-holder an intermittent rotating movement between the blows of the hammer during the operation of drilling, substantially as hereinbefore described.

3. In combination with the barrel of a rock-drilling machine which is arranged to be guided and fed forward on a steadyng-bar, A, the adjustable friction-brake for regulating the feed of the machine, substantially as hereinbefore described.

4. The cam-shaft D, having the two cranks E, held in the barrel C, and in suitable bearings thereon, and carrying the long cams V, in combination with the spring-hammer K, having the arms R, with their studs and friction-rollers, substantially as and for the purpose hereinbefore described.

20 5. The cam-shaft D, having the cranks E for operating it, and carrying the short cams X, in combination with the cross-head l on the rear end of the tool or drill holder, and the coil-spring S, arranged and applied on the forward end of the drill-holder, substantially as and for the purpose hereinbefore described.

6. The hammer, in combination with the drill-holder for receiving the blows of the hammer and communicating them to the drill, substantially as described.

30 7. The combination of the drill-holder, which receives the blows of the hammer on one end and is provided at the other end with means for attaching the drill with the barrel for securing the drill-holder in position, and the hammer for giving motion to the drill-holder, substantially as described.

8. The combination of the drill-holder having a cross-head with the barrel and directing or supporting mechanism, so that as the drill advances the cross-head will force the barrel forward on the directing or supporting mechanism, substantially as described.

40 9. The combination of the drill-holder with the spring for forcing the face of the drill into contact with the rock preparatory to receiving the stroke of the hammer.

10. In combination with the drill, a swinging hammer actuated by the force of a flat spring, substantially as described.

50 11. In combination, a barrel to hold and present the drilling mechanism, a tool-holder to receive in its front end the drilling-tool, and working in a bore or socket in the barrel, an operating-shaft provided with suitable devices for working the drilling mechanism that operates upon the tool-holder, and the steadyng-bar on which the barrel is supported and fed forward, and the adjustable legs and supports, substantially as hereinbefore described.

60 12. In combination, the tool-holder L, hav-

ing a socket in the forward end to receive and hold the drilling-tool, and provided with spiral grooves w in its surface, in combination with the ratchet-face nut T, having the spiral ribs 65 or splines v in its bore, to engage with the grooves in the tool-holder, and held in an opening in the barrel of the machine, and controlled in its rotation in one direction by a pawl, u, but left free to rotate in the other direction, substantially as and for the purposes hereinbefore described.

13. In a rock-drilling machine for drilling in rock and other substances, the spring-hammer operated in one direction, or backward, by mechanism from a rotating shaft, and in the other direction, or forward, by the reaction of the spring, to deliver a succession of blows against the end of a tool-holding bar, substantially as herein described.

75 14. The combination of a rock-drill and guides for supporting the same with a friction device, substantially as described, constructed to allow the frame carrying the drill or operating mechanism to travel in proportion to the cut of the 85 drill, as set forth.

15. The drill-holder and mechanism for guiding the same, combined with the hammer and supporting mechanism, substantially as described, so that as the drill advances the guiding mechanism will be forced forward by the 90 inertia of the hammer.

16. The drill-holder combined with the hammer-bearing mechanism and supporting mechanism, so that as the drill advances the inertia 95 of the hammer will carry the hammer-bearing mechanism forward, substantially as described.

17. The tool-holding bar L, having in one end the pocket to receive and hold the drilling-tool and at the other the detachable and removable striking-pin p, against which the blows of the hammer K are applied, substantially as hereinbefore described.

18. In a machine for drilling in rock and other substances, having a steadyng-bar, A, the extensible supporting-leg 2, 3, 5, having an adjusting-nut, 6, adapted to be attached to the rear end of the steadyng-bar, substantially as hereinbefore described, for the purposes set forth.

19. In combination with the barrel C and the steadyng-bar A, the adjustable friction-brake for regulating the feed of the machine, having the spring for producing a yielding pressure on the brake, substantially as described.

20. In combination, the barrel C, drill-holder L, and cross-head y, with the washer or cushion d, substantially as described.

HENRY F. PARSONS.
